R. ENGEBRETSSEN

ANTENNA

Filed Dec. 3, 1924

Ragnvald Engebretsen
INVENTOR

BY
Victor J. Evans

ATTORNEY

WITNESS:

John Grotton

UNITED STATES PATENT OFFICE.

RAGNVALD ENGEBRETSEN, OF BROOKLYN, NEW YORK.

ANTENNA.

Application filed December 3, 1924. Serial No. 753,730.

This invention relates to improvements in antennæ for use in radio communication.

The principal object of the invention is the provision of an antenna for use in receiving electrical wireless waves in all directions, without necessitating adjustment of the antenna thereby greatly increasing the efficiency of the radio receiving apparatus.

Another object of the invention resides in 10 an antenna in the form of a globe or circular cage formed of a mesh of intersecting wires of conducting material and which globe is mounted upon a base or pedestal for supporting the structure upon the roof of a building 15 or the like.

A further object is to provide a globular antenna for use in either receiving or broadcasting wireless waves.

With these and other objects in view, the 20 invention resides in certain novel construction and combination and arrangement of parts, the essential features of which are hereinafter fully described, are particularly pointed out in the appended claim, and are 25 illustrated in the accompanying drawing, in which:—

Figure 1 is a side elevation of my improved antenna.

Figure 2 is a vertical sectional view of the 30 line 2—2 of Figure 1.

Figure 3 is a horizontal sectional view on the line 3—3 of Figure 1.

Figure 4 is a detail view of a modified form of frame.

Figure 5 is a detail view of one of the 35 collapsible bands.

Referring more particularly to the drawing, the reference numeral 10 designates my improved antenna in its entirety and which 40 includes a globular cage 11, and a supporting structure 12.

The globular cage 11 comprises a pair of opposed end plates 13, which are connected by semi-circular wires or arcuate shaped 45 members 14 which extend radially from the vertical axis of the cage in equi-distantly spaced relation. Extending circumferentially and horizontally about the members or wires 14 are annular rings or bands 15, which 50 rings are arranged in equi-distantly spaced relation and intersecting the wires 14 at which points the wires are soldered together to provide a rigid structure. The wires 14 and 15 are of copper material, it having been proven

that such material produces the maximum 55 result although any other suitable conducting material may be employed if desired.

The points of intersection of the wires 14 and 15 are connected by cross wires 17 of a finer gauge material than the wires 14 and 15, which increases the capacity of material as it has been found that a device of this nature constructed of approximately one-hundred feet of wire will produce the desired 60 result. Cross wires 16 are likewise soldered 65 to the intersection of the wires 14 and 15. The supporting structure 12 above referred to comprises a base 17 having suitable openings therein for the passage of fastening elements such as screws for attaching the device 70 to the roof of a building, and rising from the base is an upright or post 18 on which the cage is mounted. The mast is of insulating material to prevent wireless waves from being 75 ground. The mast is also hollow for a portion of its length adjacent the top and receives a lightning rod 19 which projects above the top of the globular cage and which may be connected with the ground in any suitable manner. This rod serves to protect the cage 80 from being struck by lightning, it being understood that lightning when it strikes usually strikes the highest point.

The lead-in wire 20 which connects the antenna with the receiving apparatus is 85 formed with branches 21, one branch being connected to each of the respective wires or bands 14 adjacent the bottom of the cage, thereby providing a direct lead-in from the different radial directions of the cage. 90

From the foregoing description, it will be seen that my invention will be found convenient for use by amateurs in radio reception as the same may be easily placed in position upon a building without detracting 95 from the appearance of the same. Of course, the cage can be increased in size and mounted upon a suitable tower for use when employed for receiving or broadcasting on an extensive basis.

In Figures 4 and 5, I have shown a slightly modified form in which each of the semi-circular wires 13' has its ends formed with a disk, the disks being rotatably connected one over the other as at 22 whereby they may 105 be spread to a radial position to receive the annular bands 14', or moved together when not in use.

The bands 14' are formed of a pair of semi-circular sections 23 connected by clips or the like 24, whereby they may be moved to a position one over the other when not in use, and 5 when in use the same constitute an annular band similar to that shown in the preferred form. Any suitable means such as wire connectors may be employed for holding the bands 14' in position upon the wires 13'. 10 This form of the invention will be found convenient for shipping and storing purposes.

While I have described what I deem to be the most desirable embodiment of my invention, it is obvious that many of the details 15 may be varied without in any way departing from the spirit of my invention, and I therefore do not limit myself to the exact details of construction herein set forth nor to any

thing less than the whole of my invention limited only by the appended claim. 20

What is claimed as new is:—

An antenna comprising a plurality of spaced arcuate members arranged in globular formation and having their ends converging toward each other and fixedly connected 25 together, spaced annular bands extending circumferentially about said arcuate shaped members and fixedly connected thereto, cross wires connecting intersecting portions of said members and said bands and fixed thereto, 30 and lead-in wires joined to the respective arcuate shaped members.

In testimony whereof I have affixed my signature.

RAGNVALD ENGBRETSEN.
